UNITED STATES PATENT OFFICE.

HILDING A. SJODAHL AND JAMES H. FICHTER, OF CINCINNATI, OHIO, ASSIGNEES
TO THE CHATFIELD MANUFACTURING COMPANY, OF CINCINNATI, OHIO, A COR-
PORATION OF OHIO.

SHINGLE.

Application filed July 10, 1924. Serial No. 725,859.

To all whom it may concern:

Be it known that we, HILDING A. SJODAHL and JAMES H. FICHTER, citizens of the United States of America, and residents of Cincinnati, in the county of Hamilton and State of Ohio, have invented new and useful Improvements in a Shingle, of which the following is a specification.

An object of our invention is to provide a shingle that may be utilized in providing a new and novel design for a roof or wall covering.

Another object of our invention is to provide a shingle wherewith a large roof coverage may be attained with a relatively small number of shingles.

Another object of our invention is to provide a shingle wherewith adequate protection of the roof may be attained, notwithstanding the configuration of the roof and the relatively small number of shingles necessary for covering a given area of roof.

Another object of our invention is to provide a shingle that will readily adapt itself to produce a plurality of roof designs.

These and other objects are attained by the means described herein and disclosed in the accompanying drawings, in which:

Fig. 1 is a view of a shingle embodying our invention.

Fig. 2 is a view showing one method of producing shingles embodying our invention, from a sheet of shingle material.

Fig. 3 is a view of one design that may be produced with shingles embodying our invention.

Figs. 4, 5 and 6 are views showing other designs that may be made with shingles embodying our invention.

The shingle disclosed herein may be made of any suitable material, for example impregnated felt or the like over which is superposed a layer of crushed slate or the like, as is commonly used for providing shingles of this nature. The figure shown in Fig. 1 is provided along its lower edge with alternate flaps 10 and recesses 11 that are substantially identical in form. The recesses and the flaps are reversed end for end and side for side. By this is meant that the angular edge 12 of the flap 10 also forms an angular wall for the recess 11 while the wall 13 of flap 14, and which wall is per-

pendicular to the rear edge 15 of the shingle 16, serves as a perpendicular wall for the recess 11. In other words, the perpendicular wall 13 of the recess 11 is disposed adjacent the perpendicular wall of one flap adjacent the recess 11 while the angular wall 12 of said recess is disposed adjacent the angular edge of a second flap adjacent the said recess 11. The lower edge 17 of the flap 10 is parallel with the upper edge 18 of the recess 11 and both said edges are substantially parallel with the upper or inner edge 15 of the shingle 16. As disclosed herein the edge 12 extends between the edges 17 and 18 at an angle of 45 degrees to each of said edges.

By reference to Fig. 1 it will be observed that elongated hexagonal figures 20 may be produced over a given surface by laying the succeeding shingles in such position that the angular edges 12 of each succeeding superposed shingle are disposed in parallelism with one another and so that the perpendicular edge 13 of each flap will have its lower edge disposed at the upper end of such angular edge 12 of the shingle next below, and will have its upper edge disposed at the lower edge of the angular edge 12 of the shingle next below.

By reference to Fig. 4 it will be observed that succeeding shingles are so positioned that the perpendicular edges 13 of superposed shingles are disposed slightly to the left of the similar edge of the shingle next below, as a result of which a polygonal shaped figure is produced. It will be noted that all of the polygonal shaped figures 24 are identical wherefore a composite symmetrical design is effected notwithstanding the irregularity of the polygonal figures 24.

In Fig. 5 the shingles are so disposed that the angular lines 12 of superposed shingles extend in continuity thereby providing diagonal parallel lines that set off polygonal shaped figures 25 that effect a design forming a generally harmonious appearance notwithstanding the irregularity of the figures 25.

In Fig. 6 the angular lines 12 are offset to some extent whereby to provide superposed polygonal figures 26. It will be observed that in this design a generally harmonious appearance is effected for the whole

surface although the individual designs 26
are irregular.

What we claim is:

1. A shingle of the class described having 5
along its lower edge alternate flaps and re-
cesses, uniform in shape but reversed end
for end and side for side, each flap having
its lower edge extending in parallelism with
the rear edge of the shingle and having a
10 lateral edge extending from the lower edge
of said flap at an angle of substantially 45
degrees, and having a second lateral edge
extending substantially perpendicularly to
the lower edge of the flap.
- 15 2. A shingle having a flap and a recess
at its lower edge, the flap having a bottom
edge and a pair of lateral edges defining the
entire length of the flap, one lateral edge
extending at right angles to the width of
20 the shingle and the other lateral edge ex-
tending at other than a right angle to the
width of the shingle.
- 25 3. A shingle having a flap and a recess at
its lower edge, the flap having a bottom
edge and a pair of lateral edges defining the
entire length of the flap, one lateral edge

extending at right angles to the width of
the shingle and the other lateral edge ex-
tending at other than a right angle to the
width of the shingle, the bottom edge ex-
tending at right angles to the first mentioned
lateral edge. 30

4. A shingle having a flap and a recess at
its lower edge, the flap having a bottom
edge and a pair of lateral edges defining 35
the entire length of the flap, one lateral
edge extending at right angles to the width
of the shingle and the other lateral edge
extending at other than a right angle to the
width of the shingle, the recess being simi-
40 lar in shape to the flap and inverted where-
by to dispose the right angle side of the
recess at the first mentioned lateral edge of
the flap and the opposite side of said recess
at the second mentioned lateral edge of the 45
flap.

In testimony whereof, we have hereunto
subscribed our names this 5th day of July,
1924.

HILDING A. SJODAHL.
JAMES H. FICHTER.

surface although the individual designs 26 are irregular.

What we claim is:

1. A shingle of the class described having 5 along its lower edge alternate flaps and recesses, uniform in shape but reversed end for end and side for side, each flap having its lower edge extending in parallelism with the rear edge of the shingle and having a 10 lateral edge extending from the lower edge of said flap at an angle of substantially 45 degrees, and having a second lateral edge extending substantially perpendicularly to the lower edge of the flap.

15 2. A shingle having a flap and a recess at its lower edge, the flap having a bottom edge and a pair of lateral edges defining the entire length of the flap, one lateral edge extending at right angles to the width of 20 the shingle and the other lateral edge extending at other than a right angle to the width of the shingle.

25 3. A shingle having a flap and a recess at its lower edge, the flap having a bottom edge and a pair of lateral edges defining the entire length of the flap, one lateral edge

extending at right angles to the width of the shingle and the other lateral edge extending at other than a right angle to the width of the shingle, the bottom edge extending at right angles to the first mentioned lateral edge.

30 4. A shingle having a flap and a recess at its lower edge, the flap having a bottom edge and a pair of lateral edges defining 35 the entire length of the flap, one lateral edge extending at right angles to the width of the shingle and the other lateral edge extending at other than a right angle to the width of the shingle, the recess being similar 40 in shape to the flap and inverted whereby to dispose the right angle side of the recess at the first mentioned lateral edge of the flap and the opposite side of said recess at the second mentioned lateral edge of the 45 flap.

In testimony whereof, we have hereunto subscribed our names this 5th day of July, 1924.

HILDING A. SJODAHL.
JAMES H. FICHTER.

Certificate of Correction.

It is hereby certified that in Letters Patent No. 1,546,868, granted July 21, 1925, upon the application of Hilding A. Sjodahl and James H. Fichter, of Cincinnati, Ohio, for an improvement in "Shingles," an error appears in the printed specification requiring correction as follows: Page 2, line 9, claim 1, for the words "rear edge" read *width*; and that the said Letters Patent should be read with this correction therein that the same may conform to the record of the case in the Patent Office.

Signed and sealed this 26th day of January, A. D. 1926.

[SEAL.]

WM. A. KINNAN,
Acting Commissioner of Patents.
